METHOD OF DISTRIBUTING LIQUID.

1,239,168

Specification of Letters Patent. Patented Sept. 4, 1917.

Original application filed December 27, 1909, Serial No. 535,129. Divided and this application filed April 29, 1911. Serial No. 835,221.

To all whom it may concern:

Be it known that I, AUBREY G. ENEAS, a subject of the King of Great Britain, and a resident of Winthrop, in the county of Suffolk and State of Massachusetts, have invented an Improvement in Methods of Distributing Liquid, of which the following description, in connection with the accompanying drawings, is a specification, like characters on the drawings representing like parts.

This application is a division of the invention disclosed in my parent application Serial No. 535,129, filed December 27, 1909.

15 This invention relates to methods of distributing fluid, preferably a liquid, over an extended area. In order that the principle of the invention may be readily understood, I shall proceed to describe the best 20 mode or manner known to me for carrying into effect my method and one form of nozzle by which my said method may be practised.

In the accompanying drawings,—

25 Figure 1 is a side elevation of a spray nozzle by which I may practice my method;

Fig. 2 is a plan view of the inner liquid guiding member thereof;

30 Fig. 3 is a central longitudinal section taken through the inner and outer chambers of the nozzle shown in Fig. 1; and

Fig. 4 is a side elevation of the inner liquid guiding member.

35 In accordance with and in carrying out the method of my invention, I form and distribute over an extended area a spray composed of water or other liquid and which is, in the most effective embodiment thereof, of substantially uniform homogeneity throughout. Such spray is capable of use in many and varied relations. Among other uses, to which I am in no wise limited in the practice of my method, I may enumerate the following,—for aerating municipal and other 40 water supplies in reservoirs or other places; in connection with cooling ponds to spray the water heated in condensers of turbine and other engines; for spraying effluent in connection with sprinkling filter beds; for precipitating coal dust; for washing air; for condensing vapors; for humidifying air in chemical plants and in cotton mills; in connection with oil burners and fire extin-

guishers; and for many other uses not herein necessary to enumerate. I shall proceed to 55 describe one form of means for practising my process and one way in which a flaring spray of substantially uniform homogeneity in cross section may be secured.

In carrying out my method, I preferably 60 project the liquid, of whatever nature, in a flaring spray, with the central portion thereof of directly flaring and the circumferential portion thereof flaring along lines extending circumferentially of but eccentric the 65 axis of the central portion, the spray mass being modulated from one to the other in the intervening or between zones. Preferably in effecting this method, I simultaneously 70 produce both rotary and non-rotary jets, and mix, mingle or blend said jets within a confined space, from which I cause the said mixed, mingled or blended mass to issue in a spray of substantially uniform homogeneity.

75 Preferably the non-rotary jet is a central or axial one and the rotary jet or jets surround the same and are caused transversely to impinge upon the axial or central jet with the result that said jets are sufficiently 80 mixed to produce a spray of the character described when discharged from the confined space. In carrying out my method, I preferably provide a chamber in advance of the jet producing means, the said chamber 85 being so shaped and of such volume as to permit an effective mixture or blending of the jets before they issue in spray form from said chamber. This result may be effected by so shaping the chamber or so positioning an abutment therein as to cause impact thereon of one or more of the surrounding jets and rebound thereof, with the result of a mixing or blending of the jets within the confined space.

95 In the drawings, I have shown the preferred form of nozzle for practising my method, the said nozzle being represented as comprising a shell or casing 1 constituting an outer mixing chamber and having an 100 entrance 2 for the water or other liquid to be sprayed and a discharge orifice 3. The nozzle may be suitably connected to a hose or other means for conveying the fluid to be sprayed. For this purpose, I have herein 105 represented the shell or casing as interiorly

threaded at 4. Within the shell 1 form or position an inner guiding member 5, herein represented as detachable from the shell 1 and as exteriorly threaded at 6, so that it 5 may be screwed into position in the shell, thus forming the mixing chamber 10. Obviously, the method is not dependent upon the particular form of inner guiding member 5 or the means for positioning or forming 10 the same within the shell or casing.

The inner member 5 may be constructed in any suitable manner to produce the desired results. In order to effect the spraying referred to, I preferably so construct the inner 15 liquid guiding member 5 that it will discharge or direct into the mixing chamber 10 a plurality of jets. For this purpose I may and preferably do employ a single central jet and one or more exterior jets which, if a 20 plurality thereof be employed, surround the central jet. Preferably at least one of these divergent jets is a whirling one, said whirling jet being given a rotating or whirling character in any suitable manner. While 25 my invention may be practised by the formation of a central rotating or whirling jet and a surrounding non-rotary jet or jets, I preferably form a central or axial non-rotating jet and one or more surrounding rotary jets. It is clearly to be understood that 30 (referring to the disclosed embodiment of means) the character and arrangement of the jets that are mixed within the confining wall may be otherwise varied or altered 35 within the broad scope and purpose of my invention, the latter being to cause the breaking up of the stream-like character of the liquid, and the thorough mixing of constituent particles thereof within the nozzle, 40 and to effect the issuance thereof in a spray of substantially uniform homogeneity in transverse section.

In accordance with my method, I distribute liquid over an extended area by introducing 45 the liquid in a stream into a nozzle comprising a chamber formed by a fixed, surrounding, confining wall; breaking up the stream and finally in effecting the remixing of the constituent particles of the 50 stream within said chamber, thereby effectively breaking up the stream-like character of the liquid and remixing its constituents; and compelling issuance of said mixed constituent particles from said chamber in a 55 flaring spray of substantially uniform homogeneity in transverse section.

In the nozzle herein illustrated, the central jet is produced by the central passage 7 formed in the liquid guiding member 6 and 60 receiving the water or other liquid or fluid directed thereto under pressure and from any suitable source. Surrounding the central straight passage 7 are a plurality of divergent curved passages 8 formed between 65 the wall of the central passage 7 and the ex-

terior wall of the member 5. These passages 8 likewise receive liquid or fluid under pressure from the same source and impart a whirling or rotating action to the jets passing therefrom. The jets passing through 70 the passages 7 and 8 are primarily of equal velocity, but the velocity of the jets passing through the passages 8 is reduced below that of the central jet, owing to the contact of said surrounding jets with the inner wall of 75 the mixing chamber 10. The jets passing through said passages 7 and 8 converge and meet within the mixing chamber 10, the tapering formation of this chamber 10 compelling the mixing of said jets. The impinging of the jets upon each other thoroughly breaks them up and compels a thorough mixing and distribution of the constituent parts thereof, so that as the liquid emerges from the nozzle, it spreads in a 85 spray cone whose apex is the orifice of the nozzle, the spray being substantially uniformly and thoroughly distributed throughout the entire cone.

In other spraying nozzles with which I am 90 familiar, the spray is discharged in a cone, but the spray is substantially confined to elements of the cone, so that in reality the spray emerges in a sheet of conical form, it being also common to provide a central jet 95 discharged unmixed with the conical sheet but intended for ornamental effect merely. By my method I produce a spray so uniformly distributed that were sections taken through the cone to which I have referred, 100 they would exhibit a substantially uniform distribution of the spray throughout such section. This uniform distribution is due to the mixing compelled by the jets 7, 8 and the distribution in all directions resulting therefrom. I am aware that whirling members 105 have been positioned within nozzles and provided with passages for the liquid to be sprayed, but the result of such construction is to impart merely a centrifugal action to 110 the spray so that in effect merely a shell or conical sheet is formed.

If desired, I may provide means for introducing air into the mixing chamber 10, in order to compel a more thorough intermingling of the jets. While this may be done in any suitable manner, I have herein represented air passages 9 formed in the walls of the member 5 and admitting external air into the interior of the mixing chamber 10. 115 Each air passage 9, if employed, is preferably of the general angular character shown, so as to introduce the air along radial lines and to discharge the same substantially axially and at points surrounding the central jet issuing through the passage 7.

It will be apparent that within the mixing chamber 10, a partial vacuum is formed between the jets issuing between the passages 7 and 8. Owing to the formation of this 130

partial vacuum, the external air is sucked in through the passages 9, and although entering at atmospheric pressure, it has greater pressure imparted thereto by the jets issuing through the passages 7 and 8. It is evident that the external air may be admitted, if at all, in any suitable manner, and that if desired air primarily under greater than atmospheric pressure may be utilized. It will be apparent that the air, when employed in any form of my invention, tends further to atomize the fluid at its exit from the nozzle by reason of the expansion of the air after its discharge from the nozzle.

15 It will be evident that the mixing chamber is relatively large compared to the orifice through which the fluid escapes from the nozzle and that the chamber is of sufficient volume and so shaped as to permit and effect 20 blending or mixing of the jets before issuance from the nozzle. In that form of nozzle herein illustrated, the chamber is so shaped as to direct the rotating jet or jets across the path of the axial jet within the 25 chamber before the jets issue from the nozzle, thereby to cause said rotating jet or jets to be sprayed by said axial jet, so as to increase the spraying angle and form a full spray. In that form of nozzle herein shown, 30 the cross sectional area of the mixing chamber exceeds the combined cross sectional area of the axial and surrounding jets.

It will be apparent from the foregoing description that in accordance with my 35 method, the fluid of the jets is mixed or blended within a confined chamber, and that the mixed mass issues therefrom in a spray, which is of substantially uniform homogeneity throughout.

40 Having thus described my method and one form of means by which the same may be practised, I desire it to be understood that although specific terms are employed, they are used in a generic and descriptive 45 sense and not for purposes of limitation, the scope of the invention being set forth in the following claims.

1. That method of distributing liquid over an extended area which consists in 50 simultaneously producing an inner jet and one or more surrounding jets, in causing the mixture of said jets within a confined space, and the issuance of said jets from said space in a spray of uniform homogeneity.

2. That method of distributing liquid 55 over an extended area which consists in mixing a plurality of jets within a fixed, surrounding, confining wall and in compelling issuance of said mixed jets from said wall in a flaring spray of substantially uniform homogeneity.

3. That method of distributing liquid over an extended area which consists in mixing an inner and one or more surrounding jets within a fixed, surrounding, confining 65 wall and compelling issuance of said mixed jets from said wall from said confined space in a flaring spray of substantially uniform homogeneity.

4. That method of distributing liquid 70 from an extended area which consists in mixing a plurality of jets within a fixed surrounding confining wall, in introducing air within said confining wall and in compelling issuance of said mixed jets from said wall 75 in a flaring spray of substantially uniform homogeneity.

5. That method of distributing liquid over an extended area which consists in mixing an inner and one or more surrounding 80 jets within a fixed surrounding, confining wall, in introducing air within said confining wall, and in compelling issuance of said mixed jets from said wall in a flaring spray of substantially uniform homogeneity. 85

6. That method of distributing liquid over an extended area which consists in introducing the liquid in a stream into a nozzle comprising a chamber formed by a fixed, surrounding, confining wall; in breaking up 90 the stream and finally in effecting the remixing of the constituent particles of the stream within said chamber, thereby effectively breaking up the stream-like character of the liquid and remixing its constituents; 95 and compelling issuance of said mixed constituent particles from said chamber in a flaring spray of substantially uniform homogeneity in transverse section.

In testimony whereof, I have signed my 100 name to this specification in the presence of two subscribing witnesses.
